E. P. MULL

WATER COOLER

Filed Sept. 6, 1922

Inventor.

Edgar P. Mull

By Percy A. Moore
Attorney.

UNITED STATES PATENT OFFICE.

EDGAR P. MULL, OF TOLEDO, OHIO, ASSIGNOR TO THE ALLEN FILTER COMPANY, OF TOLEDO, OHIO.

WATER COOLER.

Application filed September 6, 1922. Serial No. 586,494.

To all whom it may concern:

Be it known that EDGAR P. MULL, a citizen of the United States of America, residing at Toledo, in the county of Lucas and State of Ohio, has invented certain new and useful Improvements in Water Coolers, of which the following is a specification.

My invention relates to water coolers and more particularly to the type known as coil coolers.

The principal object of my invention is to provide a cooler coil of such resiliency for supporting the ice that the coil is not liable to become damaged when a fresh cake of ice is placed in the water cooler, and in contact with the coil.

It is advisable in the so called coil type of coolers to locate the cooler coils at the bottom of the cooler where they do not interfere with the placing of the ice cake in the cooler.

Furthermore when so positioned the ice will rest upon and always be in contact with the coils and consequently a maximum of refrigeration obtained. However, the placing of the cooler coil upon the bottom of the cooler has proven objectionable due to the fact that the coils would frequently become crushed or damaged by being jammed against the bottom of the cooler, particularly where the ice cake slipped when a fresh cake was being placed in the cooler.

Others have sought to overcome this objection by the use of false bottoms placed above and out of contact with the coils, but as previously stated maximum cooling of the coils can not be had except where the ice is in direct contact with the coils. It is the purpose of the present invention to overcome these disadvantages.

In the accompanying drawings forming part of this application:

Figure is a perspective view partly broken away of an ice cooler showing my invention.

Referring more particularly to the drawings forming part of this specification, 5 denotes a cooler or ice box comprising spaced side, end and bottom walls 6, having a cork or other suitable insulating filling 7. A suitable cover 8, seals the top opening 9, of the cooler.

10, is a water inlet pipe extending through the bottom of the cooler and leading from

any suitable source of water supply (not shown). A water outlet pipe or coupling 11, extends through one of the side walls of the cooler, and is connected at its outer end to any suitable faucet 12.

The cooling coil 13, comprises a series of bends or convolutions 14, of progressive height from the bottom coil or bend 15, to the top coil 16. The convolutions or bends preferably are of increasing size from the bottom bend upwardly and preferably more or less concentric but this is not absolutely necessary, the essential feature being that they are graduated in height in order to provide a resilient seat for the cake of ice 17. To this end preferably only the bottom convolution or bend 15, normally engages the bottom wall of the cooler, but more than one bend may so engage.

The top convolution or bend 16, is connected to the water outlet pipe 11, and the bottom convolution or bend 15, is connected to the inlet pipe 10. A waste pipe 20, the upper end of which is above the horizontal plane of the top convolution or bend 16, of the cooler coil, provides for suitable drainage.

In placing the ice in the cooler the former is inserted through the top opening 9, of the cooler, onto the top convolution or bend 16, the convolutions or bends giving in turn until the ice is resiliently supported thereon, all shock and jar being absorbed thereby. The weight of the ice in contact with the convolutions or bends of the cooler coil causes the ice to drop down as the said bends eat into the cake of ice. As the bends become increased in the cake, the former are gradually brought up to the temperature of the ice and in consequence the melting of the ice thereafter becomes very slow.

Having thus described my invention, what I claim as my invention is:

1. A water cooler comprising an ice box having a water inlet and a water outlet, a resilient refrigerating coil connected at opposite ends to said inlet and outlet respectively, said coil having bends or convolutions graduated in height, the bottom most of said coils resting on the bottom of said ice box.

2. A water cooler comprising an ice box having a water inlet and a water outlet, a

resilient refrigerating coil having bends or convolutions of graduating height and circumference, the topmost of said bends connected to the water outlet, and the bottom 5 most of said bends normally seated on the bottom of the ice box and connected to said water inlet.

In testimony whereof I affix my signature in presence of two witnesses.

EDGAR P. MULL.
